TURRET GUN MOUNTING

Lewis Motley, London, England

Application May 12, 1947, Serial No. 747,428
In Great Britain October 12, 1942Section 1, Public Law 690, August 8, 1946
Patent expires October 12, 1962

7 Claims. (Cl. 89—37)

1

This invention relates to gun mountings and refers more particularly to gun mountings in which the gun is adapted to be fired from behind massive armour protection, as for example the armoured turret of a tank.

The object of the invention is the provision of improved means for taking the recoil of the gun, and the invention consists broadly in the arrangement that the massive armour protection forms the support on which the gun is mounted, and moves together with the gun in both traverse and elevation, and also moves through a small distance to absorb the recoil.

By the expression "massive" it is to be understood that the armour protection is so massive in relation to the calibre of the gun that its rearward recoil upon firing of the gun would be relatively slow even if it were unsupported. For example armour protection of two or three tons weight would be suitable for a six pounder gun.

Preferably resilient means for resisting the recoil of the massive armour protection and effecting the counter recoil are provided, the arrangement being such that the amplitude of recoil is reduced to a matter of fractional inches.

In order that the invention may be the more clearly understood, a gun mounting in accordance therewith employed on a tank will now be described, reference being made to the accompanying drawings, wherein:

Figure 1 is a sectional side elevation of said mounting;

Figure 2 is a rear elevation shown in section on line II—II of Figure 1.

Figure 3 is a sectional plan on line III—III of Figure 1;

Figure 4 is a sectional elevation illustrating a modified form of a detail.

Referring to the drawings the main gun 1 is mounted on the upper portion or head 2 of a gun turret. Said head 2 which constitutes a massive armour protection for the gunner is mounted on a lower portion or base 3 of said gun turret in such a way as to be rotatable relative to said base about a horizontal axis X—X which is at right angles to the gun. Said turret base 3 is rotatable about a vertical axis Y—Y relative to the tank itself. Thus for training the gun in traverse said turret base 3 and therefore the whole turret together with the gun, is rotated about said vertical axis Y—Y, and for adjusting said gun in elevation the turret head 2 is rotated about the axis X—X relative to the turret base 3. In other words, the turret base 3 forms an intermediate element whereby the head 2 and gun 1 are

2

mounted on a relatively fixed base constituted by the tank itself, so that said head and gun can move both in traverse and elevation.

The gun 1, which may be a six pounder, may be rigidly bolted to the turret head 2 or it may be mounted on said turret head in such a way as to be capable of recoiling relative thereto in opposition to springs through a small distance only, of say two or three inches. In either case the major part of the recoil is taken by the turret as a whole. As the turret head is heavily armoured and is therefore massive (it may for example weigh three tons or more) the recoil movement of the turret will only be slow and need only have an amplitude of a fraction of an inch. To provide for such recoil movement of the turret, the turret base 3 at its upper end rotates in an upper journal bearing 4 which is of such a character as to permit of a small horizontal movement in any direction of the upper end of said turret base to absorb the recoil, and, at its lower end, said turret base is mounted on a supporting member 5 which rotates about the vertical axis Y—Y, the mounting of said turret base on said supporting member being through the medium of a universal joint which permits said turret base to pivot slightly in any direction about a point Z on said axis Y—Y just below said turret base. The member 5, which, as will hereinafter appear, is rotatable by a source of power, thus constitutes a driving element for rotating the turret base 3.

The turret base 3 is of generally cylindrical form and the upper journal bearing 4 comprises a large horizontal bearing ring 4a surrounding, and mounted rigidly on, the upper end of the turret base 3, and a race of relatively small horizontal wheels 4b with resilient tyres and anti-friction (say ball) bearings mounted on the tank structure 6 around said horizontal bearing ring 4a so as to engage the outer surface thereof. It will be seen that as the turret base 3 rotates the bearing ring 4a will run freely over the horizontal wheels 4b and that, when the gun 1 is fired, the resilient (say rubber) tyres of said wheels will yield sufficiently to enable the upper end of the turret base to make the horizontal movement aforesaid.

The supporting member 5 is mounted on the floor of the tank and rotates in ball bearings 7 (which locate it axially) and on conical roller bearings 8 (which support the downward thrust) in a manner which is deemed clear from the drawings. The universal joint between the turret base 3 and the member 5 comprises a member

9 from which project four horizontal trunnions 10 at right angles to each other and radial with respect to the point Z. One opposite pair of said trunnions bear respectively in lugs 11 which depend downwardly from the bottom of the turret base, and the other opposite pair of said trunnions bear respectively in lugs 12 which stand upwardly from the supporting member 5. It will thus be seen that the turret base is capable of rocking universally about the axes of both pairs of trunnions.

The mounting of the turret head 2 on the turret base 3 is through massive trunnions 13 which project inwardly from the sides of the turret head and bear in massive supporting plates 14 up-standing from the turret base. These supporting plates 14, which are of triangular form as shown, are each made in one casting with a respective arc shaped piece 15 bolted within the upper end of said turret base 3.

The sides of the turret head 2 are flat as shown and lie close against the supporting plates 14. The back of said turret head is more or less spherical and the front is shaped as shown to receive the gun. The roof of said turret head, as will be hereinafter more particularly described carries a hood 16 on which is mounted a light gun 17 of the machine gun type. The bottom of the turret head 2 is open and the gunner stands in the turret base 3 with the upper part of his body in the turret head. To fill in the space between the bottom of the turret head 2 and the top of the turret base 3, two further front and rear castings are mounted on the upper end of the turret base. The front casting comprises a spherical front plate 18 and an arc shaped piece 19 bolted within the upper end of said turret base, and also side pieces 20 extending rearwardly from the front plate 18 up to the front edges of the triangular plates 14. The rear casting comprises in like manner a spherical rear plate 21, an arc shaped piece 22 bolted within the upper end of the turret base and side pieces 23 extending forwardly from the rear plate to the rear edges of the triangular plates 14.

As shown the upper end of the turret base 3 lies just within the main armour of the tank, the reference 6 designating the roof of the said main armour.

It will be appreciated that, as the gun 1 does not have to recoil appreciably into the turret, the latter may be made considerably smaller than heretofore, and the armour can accordingly be made thicker for the same overall weight.

The ammunition for the gun is contained in an armoured magazine 24 detachably mounted on the back of the turret head, outside the turret head and communicating with the interior of the turret through a small opening 25 in the back of the turret head. It will be appreciated that the rounds in such a magazine could be detonated and ignited without the gunner being injured. The magazine which projects rearwardly from the back of the turret head as shown will, in some measure, balance the weight of the gun. The spherical rear plate 21 is cut away at 27 to accommodate a bracket or tray 26 for the rounds, and the spherical front plate 18 is, in like manner, cut away at 28 to accommodate the gun 1.

The movement both for traverse training and elevational training is effected hydraulically. Thus for movement in traverse the supporting part 5 has a worm wheel 29 rigidly mounted on it, and said worm wheel is engaged by a worm 30 driven by some form of hydraulic motor (not

shown) which is controlled from within the turret.

For movement in elevation two pairs of vertical hydraulic cylinders are mounted within the turret base 3 one pair being on each side. Each pair comprises a forward cylinder 31 in front of the axis X—X and a rear cylinder 32 to the rear of said axis X—X. Each cylinder has a piston 33 and an upwardly extending piston rod 34 which is connected by means of a connecting rod 35 to the side of the turret head at 36. Two pipes 37 and 38 are provided, either of which can, by control means, not shown, inside the turret, be connected to a source of hydraulic pressure while the other is connected to exhaust. The pipe 37 is connected to the upper end of both rear cylinders 32 and to the lower end of both forward cylinders 31, and the pipe 38 is connected to the lower end of both rear cylinders and to the upper end of both forward cylinders. Thus when the pipe 37 is connected to pressure and the pipe 38 to exhaust, the pistons of the rear cylinders will move down and those of the forward cylinders up, and the gun 1 will be elevated. On the other hand, when the pipe 37 is connected to exhaust and the pipe 38 to pressure, the pistons of the forward cylinders will move down and those of the rear cylinders up, and the gun will be depressed. As will be sufficiently clear from the drawing the conduits from the pipes 37 and 38 pass up through axial holes in the member 5, the member 9 and the bottom of the turret base 3 after which branch pipes go to the appropriate ends of the respective cylinders 31 and 32.

The hood 16 is rotatably mounted (about the aforesaid axis Y—Y) on top of the turret head 2 through ball bearings 39. The gunner's head can extend up, through a top opening, into this hood when he so desires and the hood is provided with a thick bulletproof glass front 40 through which the gunner can look. The gun 17 rotates relative to said hood about a horizontal transverse axis W—W. For movement of the gun 17 in traverse, the hood is rotated on the ball bearings 39, and for movement of said gun in elevation, said gun is rotated about the axis W—W. In the particular arrangement shown, the trunnions of the gun 17 have arms 41 rigidly mounted on them, and these arms are linked, by means of links 42, which pass through the roof of the hood, to similar and parallel arms 43 pivotally mounted on the turret head 2, within the top opening thereof, so as to be rotatable about an axis V—V parallel to the axis W—W. Thus as the arms 43 are rotated about the axis V—V, the gun 17 will be rotated about the axis W—W. To enable the arms 43 to be thus rotated they are each provided with a downward extension terminating in a handle 44. The gunner holds the handles 44 in his two hands and it is clear that by means of them he can not only rotate the gun in elevation as stated but can also rotate the whole hood and gun for traverse. The reference 45 designates a trigger by means of which the gun may be fired. Alternatively the transmission mechanism through which the gun 17 is moved in elevation could be the same as in British Patent No. 581,975. Or the gun 17 could be mounted on the head in the manner described in British Patent No. 581,973, no hood being employed.

The reference 46 designates the door by which access is had to the turret base 3. The reference 47 designates a sighting telescope for the main gun.

Figure 4 illustrates a slight modification which

has the effect that, when the turret recoils owing to discharge of the gun 1, not only the wheels 4b at the rear of the turret, but also those at the front of the turret, will be compressed. Thus, in addition to the bearing ring 4a whose outer surface is engaged by the surrounding wheels 4b the turret base 3 has a further bearing ring 4c mounted on it (shown integral with the ring 4a) whose inner surface is engaged by said wheels 4b which it surrounds. The structural details of this modification are deemed sufficiently clear from the drawing.

We are aware that a gun mounting has been heretofore proposed in which the gun, having the usual recoil absorbing means, is fired from behind massive armour protection which forms the support on which the gun is mounted and moves, together with the gun, in traverse but not in elevation, and which is also capable of moving in a vertical direction to absorb the shock of projectiles striking it.

We are also aware that a gun mounting has been heretofore proposed in which the gun, provided with the usual recoil absorbing means, has trunnions supported in bearings in a carriage which has a massive weight associated with it and which is pivoted about a transverse axis to a gimbal frame, which, in turn, is pivoted fore and aft on a horizontal ring which rotates on a non-rotatable base, spring washers being associated with the fore and aft pivots between the gimbal frame and the ring, and a cushion of elastic material being provided between the non-rotatable base and a fixed support therefor, which spring washers and cushion take up part of the recoil when the gun is fired.

I claim:

1. An armoured gun and mounting construction, comprising a gun including a gun barrel, massive armour protection defining a chamber for the gunner firing said gun, said massive armour protection including an armoured turret head which is movable about both a horizontal and a vertical axis, said gun barrel being mounted on and supported by said turret head, means for moving said turret head and said gun barrel in unison both for traverse and elevation of the gun, and supporting means including resilient recoil absorbing means for said massive armour protection affording movement of the entire massive armour protection rearwardly to absorb the recoil of the gun barrel and for restoring said massive armour protection and gun barrel to the initial position following recoil of the gun barrel.

2. An armoured gun and mounting construction, comprising a gun including a gun barrel, massive armour protection defining a chamber for the gunner firing said gun, said massive armour protection including an armoured turret head which is movable about both a horizontal and a vertical axis, said gun barrel being rigidly mounted on and supported by said turret head, means for moving said turret head and said gun barrel in unison both for traverse and elevation of the gun, and resilient supporting means for said massive armour protection affording movement of the entire massive armour protection rearwardly with said gun barrel to absorb the recoil of the gun barrel.

3. An armoured gun and mounting construction, comprising a gun including a gun barrel, massive armour protection defining a chamber for the gunner firing said gun, said gun barrel being mounted on and supported by said massive armour protection, an intermediate element on

which said massive armour protection is mounted for rotation about a given axis, a relatively fixed base on which said intermediate element is mounted for rotation about an axis which is transverse to said first-mentioned axis, whereby said massive armour protection and gun barrel are capable of being moved in unison both for traverse and elevation of the gun barrel, and resilient means coacting with said intermediate element and said base for permitting movement of said intermediate element with said massive armour protection to absorb the recoil of the gun barrel.

4. An armored gun and mounting construction, comprising a gun including a gun barrel, massive armour protection defining a chamber for the gunner firing said gun, said gun barrel being rigidly mounted on and supported by said massive armour protection, an intermediate element on which said massive armour protection is mounted for rotation about a given axis, a relatively fixed base on which said intermediate element is mounted for rotation about an axis which is transverse to said first-mentioned axis, whereby said massive armour protection is capable of being moved both for traverse and elevation of the gun barrel, and resilient means coacting with said intermediate element and said base for permitting movement of said intermediate element with said massive armour protection to absorb the recoil of the gun barrel.

5. An armoured gun and mounting construction, comprising a gun including a gun barrel, massive armour protection defining a chamber for the gunner firing said gun, said gun barrel being mounted on and supported by said massive armour protection, an intermediate element on which said massive armour protection is mounted for rotation about a horizontal axis, a relatively fixed base on which said intermediate element is mounted for rotation about an upright axis, whereby said massive armour protection is capable of being moved both for traverse and elevation of the gun barrel, said intermediate element having a circular bearing surface thereabout concentric with said upright axis, and a fixed ring of wheels surrounding said bearing surface in engagement therewith, said wheels being resiliently compressible and permitting movement of said intermediate element to absorb the recoil of the gun barrel.

6. An armoured gun and mounting construction, comprising a gun including a gun barrel, massive armour protection defining a chamber for the gunner firing said gun, said gun barrel being mounted on and supported by said massive armour protection, an intermediate element on which said massive armour protection is mounted for rotation about a horizontal axis, a relatively fixed base on which said intermediate element is mounted, a driving element mounted on said fixed base for rotation relative thereto about a vertical axis, a bearing in which said intermediate element is rotatable relative to said base about said vertical axis, a universal coupling connecting said driving element to said intermediate element, said bearing being spaced from said universal coupling in a sense longitudinally of said vertical axis, and being resilient so as to permit of movement of said intermediate element therein transversely to said vertical axis, and means for driving said driving element.

7. An armoured gun and mounting construction, comprising a gun including a gun barrel, massive armour protection defining a chamber

for the gunner firing said gun; said gun barrel being mounted on and supported by said massive armour protection, an intermediate element on which said massive armour protection is mounted for rotation about a horizontal axis for training the gun barrel in elevation, a relatively fixed base, a bearing for said intermediate element whereby the latter is adapted to rotate about a vertical axis relative to said base for training the gun barrel in traverse, a driving element rotatable about the same vertical axis, a universal coupling connecting said driving element to said intermediate element for rotation of the same by the driving element, said bearing being spaced from said universal coupling in a sense longitudinally of said vertical axis, and being resilient so as to permit of movement of said intermediate element therein transversely to said vertical axis for absorption of the recoil of the gun barrel, and means for driving said driving element.
